UNITED STATES PATENT OFFICE.

PHILIP SPENCER, OF MILLBURY, MASSACHUSETTS, ASSIGNOR TO J. H. WILLIAMS COMPANY, OF MILLBURY, MASSACHUSETTS, A CORPORATION OF NEW YORK.

SHUTTLE.

1,345,898.

Specification of Letters Patent.

Patented July 6, 1920.

Application filed August 5, 1919. Serial No. 315,376.

To all whom it may concern:

Be it known that I, PHILIP SPENCER, a citizen of the United States, residing at Millbury, in the county of Worcester and State of Massachusetts, have invented certain new and useful Improvements in Shuttles; and I do hereby declare the following to be a full, clear, and exact description of the invention, such as will enable others skilled in the art to which it appertains to make and use the same.

This invention relates to an improvement in loom shuttles and particularly to an improvement in bobbin holders for shuttles. The object of the invention is to reorganize and improve the construction of bobbin holders to simplify, strengthen and render them more efficient and better adapted to the purposes for which they are designed. To the accomplishment of this object and such others as may appear, the invention consists of the shuttle hereinafter described and claimed. In the drawings illustrating the preferred embodiment of the invention, Figure 1 is a plan of a portion of a shuttle showing the improved bobbin holder; Fig. 2 is a side elevation, partly in section; Fig. 3 is a horizontal section on line 3—3, Fig. 2; Fig. 4 is a cross-section on line 4—4, Fig. 2; and Fig. 5 is a plan of a sheet metal blank from which the improved bobbin holder is formed.

Bobbin holders as heretofore constructed have included a bobbin spring, a shield member, a spacer coöperating with the bobbin spring to maintain the ends thereof in spaced relation, and a separate shim coöperating with the shield and bobbin spring to assist in maintaining the bobbin holder in place in the shuttle body. The bobbin spring is secured to the shuttle body by a bolt extended transversely through the shuttle body and bobbin spring. The shield member is secured in place by a wood screw screwed into the top of the body portion of the shuttle.

The present invention contemplates a bobbin holder in which the usual bobbin spring coöperates with an improved shield member. The improved shield member does away with the use of the usual spacer, and the usual shims are constructed integrally with the shield member. The construction is such that the shield member is secured in operative relation to the bobbin spring

by the coöperation of the usual transverse bolt extended through the shuttle body and through the bobbin spring and a portion of the shield member itself. The improved construction of bobbin holder possesses many advantageous features as will be pointed out.

The illustrated embodiment of the invention is described as follows: The shuttle body 10 is provided with the bobbin holder 12 adapted to fit into the usual recess therein. The bobbin holder 12 comprises a bobbin spring 15 of usual or preferred construction, the leaves 16 of which are adapted to receive and hold the butt of a bobbin. A shield member 20 is adapted to coöperate with the bobbin spring 15 to form the complete bobbin holder 12. The shield member 20 comprises a bottom plate 25 having laterally extended flanges 26, an inclined guide portion 27 and a top plate 28. The top plate 28 is provided with laterally extended flanges 29 which are adapted to fulfil the functions of the separate shim used in previous constructions. The inclined guide portion 27 is provided with inwardly and rearwardly extended arms 30 having parallel portions 31 spaced a short distance from one another and arranged to coöperate with the rear portion of the bobbin spring to serve as a spacer, being forced thereby into contact with one another when the bobbin holder is assembled. The parallel portions 31 are provided with holes 32 arranged therein so as to coöperate with the usual holes in the bobbin spring 15 and to permit the usual bolt 35 to pass therethrough and to thereby secure the bobbin spring 15 and improved shield member 20 together in the recess in the body portion 10 of the shuttle, thus eliminating the wood screw heretofore employed to secure the top of the shield member to the top of the shuttle body. The top plate 28 is provided with the stamped up portion 37 which serves to strengthen and reinforce the same.

It will be observed that the construction of the improved shield member is such as to enable it to be formed from a single sheet metal blank, as indicated in Fig. 5. This feature enables the bobbin holder to be made at considerably less expense than previous bobbin holders.

When the shield member is secured in an operative position in the body portion of

the shuttle, the top and bottom plates 28, 25 are held by the flange portions 29 engaging shoulders or grooves in the body portion of the shuttle. It is to be observed that the flange portions are not secured to and do not form part of the bobbin spring 15 so that the inclined portion 27 of the shield member is permitted to yield or spring considerably more than previous shield members which were held against the bobbin spring more or less rigidly.

When one bobbin is displaced from the shuttle by the introduction of a new bobbin, the inclined portion of the shield member 15 may be subjected to heavy blows. In previous constructions the inclined portion of the shield was oftentimes distorted and dented as a result of such blows. The improved shield member 20 is reinforced by 20 the arms extended rearwardly from the mid portion thereof so that all blows upon the inclined shield member are transmitted through the arms to the bolt where they are absorbed by the body portion of the shuttle. 25 In this manner the contour and shape, together with the resiliency of the shield member, is maintained for long periods of time so that the usefulness and life of the bobbin holder is prolonged.

30 While the preferred embodiment of the invention has been illustrated and described it is to be understood that the same may be embodied in other forms within the scope of the following claims.

35 1. A shuttle having, in combination, a body portion, a bobbin holder comprising a bobbin spring, and a shield member, the shield member having an inclined portion

and two rearwardly extended arms formed integrally therewith adapted to coöperate 40 with the bobbin spring to serve as a spacer therefor.

2. A shuttle having, in combination, a body portion, and a bobbin holder comprising a bobbin spring having holes in the rear portion thereof and a shield member having an inclined portion and two rearwardly extended arms formed integrally therewith and provided with holes therein adapted to coöperate with the holes in said bobbin 50 spring to permit the insertion of a bolt therethrough for the purpose of securing the bobbin spring and shield in the shuttle body.

3. A shuttle having, in combination, a body portion and a bobbin holder comprising a bobbin spring and a shield member, the shield member having a top plate, a bottom plate, an inclined portion extended from the top to the bottom plate, and two spacing arms extended rearwardly from the 60 inclined portion formed integrally therewith and adapted to coöperate with the bobbin spring to serve as a spacer, and having provision for securing the shield member to the body portion of the shuttle. 65

4. A shuttle having, in combination, a body portion and a bobbin holder comprising a bobbin spring and a shield member, said shield member having top and bottom flanges, an inclined portion, and two rearwardly extended arms adapted to coöperate with the bobbin spring to act as a spacer therefor, said shield member being constructed of a single piece of sheet metal. 70

PHILIP SPENCER.
